(57) **CLAIM**

We claim the ornamental design for a power pedestal, as shown and described.

DESCRIPTION

FIG. 1 is a perspective view of a power pedestal.

FIG. 2 is a front view of the power pedestal shown in FIG. 1.

FIG. 3 is a rear view of the power pedestal shown in FIG. 1.

FIG. 4 is a first side view of the power pedestal shown in FIG. 1.

FIG. 5 is a second view of the power pedestal shown in FIG. 1.

FIG. 6 is a top view of the power pedestal shown in FIG. 1; and,

FIG. 7 is a bottom view of the power pedestal shown in FIG. 1.

Any broken lines represent portions of the power pedestal that form no part of the claimed design. Any dash-dot broken lines represent the boundaries of the claim. The dash-dot broken lines themselves form no part of the claimed design. The power pedestal is shown with symbolic breaks in its width and height. The appearance of any portion of the article between the break lines form no part of the claimed design.
